UNITED STATES PATENT OFFICE.

ANDREW RAICHE, OF FAIRHAVEN, MASSACHUSETTS, ASSIGNOR TO ATLAS TACK COMPANY, OF FAIRHAVEN, MASSACHUSETTS, A CORPORATION OF NEW JERSEY.

MACHINE FOR INSERTING FASTENERS.

1,119,724.

Specification of Letters Patent.

Patented Dec. 1, 1914.

Application filed April 4, 1914. Serial No. 829,536.

To all whom it may concern:

Be it known that I, ANDREW RAICHE, a citizen of the United States, and resident of Fairhaven, in the county of Bristol and State of Massachusetts, have invented certain new and useful Improvements in Machines for Inserting Fasteners, of which the following is a specification.

This invention relates to machines for inserting fasteners, and the accompanying drawings show the same as embodied in a machine for inserting lacing hooks.

Of the accompanying drawings, which illustrate one form in which the invention may be embodied:—Figure 1 represents a front elevation of a hook-setting machine, portions of which are omitted for the sake of avoiding the obscuring of other portions. Fig. 2 represents a side elevation, partly in section, of the front part of the machine, and includes some of the elements omitted from Fig. 1. Fig. 3 represents a horizontal section through the feed mechanism in the plane indicated by line 3—3 of Fig. 1. Fig. 4 represents a top plan view of the work support, hook carrier, work gage, and a portion of the presser-foot which cooperates with the work support. Figs. 5, 6 and 7 represent, on a larger scale, vertical sections in a plane from front to rear of the devices which insert and set the fasteners, and these figures show successive positions and stages of operation. Fig. 8 represents a front elevation, partly in section, of the mechanism which actuates the setting die. Fig. 9 represents a side elevation of the structure shown at the bottom of Fig. 8. Fig. 10 represents one of the cams included in Fig. 9.

40 The same reference characters indicate the same parts wherever they occur.

In the machine as illustrated there is a combined upsetting die and punch, the latter being a projection in the center of the die. The punch cooperates with a punch block to form a hole in the stock, and when the punch is in the stock it is moved laterally to feed the stock. A hook carrier is arranged to stand in the same plane as the punch block during the feeding of the stock, and during the feeding movement of the punch the stock is held on the punch by the punch block and hook carrier. The punch block is fixed, and for this reason 50 the length to which the punch may move

in punching the stock is limited by the punch block, regardless of the thickness of the stock. It is desirable, however, to flare the shank of the lacing hook according to the thickness of the stock, and for this reason I have provided means for automatically adjusting the setting die toward the hook carrier after the stock has been fed but before the upsetting die and punch are returned to their initial position. This movement of the upsetting die toward the hook carrier may occur before or after the shank of the hook has been inserted in the stock. If it occurs before the shank of the hook is inserted, the upsetting die will 65 take its final setting position while the hook carrier is descending to receive a hook or rising to insert the hook in the stock. It might also occur simultaneously with the flaring movement of the hook carrier, or it 70 might occur after the flaring movement of the carrier has been finished, without varying the result of the setting operation. The setting mechanism as illustrated is arranged to cause the aforesaid movement of the setting die toward the hook carrier after the hook carrier has completed its setting movement toward the die.

The mechanism for giving the final adjustment to the setting die is adjustable to 85 vary the length of such movement, in accordance with the thickness of the stock. When operating upon relatively thick stock this movement of the upsetting die would be relatively little, but when operating upon 90 relatively thin stock the movement of the die would be greater. Special mechanism is provided for causing this variable movement of the die. The die and punch must have an invariable punching stroke in order 95 to coact accurately with the punch block, and it would therefore be impractical to vary the length of the punching stroke for the purpose of varying the degree of flare imparted to the shank of the hook. It would 100 also be impracticable to vary the flaring of the hook by varying the movement of the hook carrier, because it is necessary for the hook carrier, when at its lowest position, to register with the hook raceway, and when 105 at its highest position to register with the punch block in order to hold the stock on the punch during the feeding movement.

When the machine is at rest the anvil and punch are elevated and are out of line with 110

the hook carrier. The top surface of the hook carrier at this time is flush with the top surface of, and contiguous with relation to, the stock-supporting element. The stock 5 is clamped primarily upon a work support by a presser-foot; and when the machine is started, the combined die and punch descend to punch a hole in the stock. When the 10 punch has completed its punching stroke, its pressure against the punch block is relieved sufficiently to permit feeding the stock, but the punch is not withdrawn from the stock. When the stock has been punched and the pressure of the punch relieved as 15 stated, the combined die and punch are moved laterally to feed the stock along the punch block to hook-receiving position. At this time the top surface of the hook carrier is flush with the top surface of the punch 20 block, and during the feeding movement the punch block and hook carrier act to keep the stock upon the punch to insure accuracy of feed. After the stock has been fed to hook-receiving position the hook carrier descends to receive a hook, the stock being 25 supported upon the punch during this interval by the stationary work support. The hook carrier, upon receiving a hook, rises and passes the shank of the hook through 30 the stock and forces the shank against the die to flare the shank.

When the setting operation has been completed, the combined die and punch are raised and moved laterally to their initial 35 position, the hook carrier in the meantime remaining stationary in the throat of the set hook. As the set hook will be moved laterally from the hook carrier by the next succeeding feeding operation, the carrier 40 will be free of the set hook before it becomes necessary for the carrier to descend to receive another hook. The presser-foot is lifted before the beginning of each feeding movement and is returned to clamping position 45 upon the completion of the feeding movement.

Referring now to the drawings, the setting die is indicated at 12, and the punch is indicated at 13. This device is affixed to a 50 plunger 14 which is arranged to slide up and down in a feed carriage 15. A head 16 is affixed to the upper end of the plunger and is formed with a groove 17 in which a sliding block 18 is arranged. This block is 55 carried by a crankpin 19 which is affixed to a rockshaft 20. The mechanism for operating the rockshaft is hereinafter described in detail.

The feed carriage 15 is arranged to slide 60 from side to side upon a guide 21 formed upon the main frame of the machine. The mechanism for transmitting feeding movement to the carriage is shown by Fig. 3. A toothed rack 22 is affixed to the carriage and 65 engages a toothed gear segment 23. The

segment 23 is compounded with a toothed segment 24, the two segments being formed integrally, in the present instance, with a hub 25. The hub is arranged to oscillate upon a stud 26. The teeth of the segment 24 are engaged by a toothed rack 27. This rack is carried by a slide 28 which is arranged to slide from front to rear on guides 29 on the main frame. Suitable means, such as a cam (not shown), is provided for reciprocating the slide 28.

The punch block is indicated at 30 in Fig. 4. It is set into a stationary work support 31 so that its top surface is flush with that of the work support. A work gage is indicated at 32 and is adjustably mounted upon the work support. A presser-foot, indicated at 33, is arranged to coöperate with the work support. The presser-foot is mounted upon a rod 34 which is arranged to slide in bearings 35. A block 36 affixed to the rod has suitable connection with a bell-crank lever 37 whose fulcrum is indicated at 38 in Fig. 2. The clamping stress and retractive movement are transmitted to the bell-crank lever 90 by a link 39. Suitable means, such as a cam (not shown), is provided for actuating the link.

The hook carrier is indicated at 40, and as shown by Figs. 5, 6 and 7, is in the form of a lip and is adapted to occupy the throat of a lacing hook α , between the head and shank of the hook. The hook carrier is affixed to a plunger 41 which is arranged to slide up and down in bearings such as that indicated at 42. The structure of the hook carrier is, to all intents and purposes, like that illustrated and described in Letters Patent 1,036,710, granted to me August 27, 1912. The plunger 41 is provided with cam rolls 43 and 44 which coact respectively with cams 45 and 46. These cams are affixed to a shaft 47. The cam 45 imparts upward movement to the hook carrier, and the cam 46 imparts downward movement. As shown by Figs. 1 and 2, the hook carrier is held so that its top surface is flush with that of the stationary work support and punch block.

Figs. 2 and 5 illustrate a raceway 48 for lacing hooks, which raceway has its delivery 115 end below the work support. At 49 in Fig. 5 is represented a device of well-known structure and operation for feeding hooks one at a time to the raceway 48. When the hook carrier is at its lowest position it is in line with the delivery end of the raceway, and the lacing hook which is supported by the raceway is transferred to the carrier by a reciprocatory pusher 50. While the hook is upon the carrier 40 it is prevented from moving laterally by a retaining device 51 which is formed to straddle the head of the hook and to engage the head at diametrically opposite points. This device is fully illustrated and described in my aforesaid 120 125 130

Patent 1,036,710. During the feeding movement of the work the device 51 is retracted to the position indicated by dotted lines in Fig. 7, but at other times the device remains in the position shown by Figs. 5 and 6. For this purpose a lever 52 and cam 53 are provided. The fulcrum of the lever is indicated at 54. The cam is carried by shaft 47. In order to maintain the desired connection between the lever 52 and the device 51 when the hook carrier is moving up and down, I provide the lever with a sliding extension 55 which is pivotally connected to the device 51. A spring 56 acting upon the lever 52 normally holds the device 51 in hook-engaging position, and retractive movement is caused by the cam 53. As shown by Fig. 1, the hook carrier 40 has laterally extending flanges which rest upon the device 51 in such manner that the stress upon the carrier, due to flaring a hook, is partly sustained by the device 51 and by the surfaces of the plunger upon which the device 51 rests.

The mechanism for reciprocating the combined punch and setting die is shown by Figs. 8, 9 and 10. For this purpose three cams are provided, and they are indicated respectively at 60, 61 and 62. These cams are all affixed to the shaft 47. Cams 60 and 61 coact respectively with rolls 60' and 61'. These rolls are carried by a link 63 whose upper end embraces a crankpin 64 fastened to the rockshaft 20. The lower end of the link 63 has sliding engagement with the shaft 47, and for this purpose is provided with a slot 65 through which the shaft extends, the shaft acting as a guide to guide the movement of the link. Dotted lines *a*, *b* and *c* in Fig. 8 indicate the several angular positions at which the crankpin dwells. When the crankpin is raised to the angular position indicated by line *a*, the punch and setting die are elevated as shown by Figs. 1 and 2. This may be regarded as the initial position of the punch and die. The cam 60 imparts downward movement to the punch to such extent as to carry the crankpin 64 from line *a* to line *b*. This cam causes the punching of the stock, and when the highest point 66 of this cam has passed the roll 60' the punching stress is relieved and the crankpin 64 springs back to the position indicated by line *c*. The position of the punch as shown by Fig. 5 corresponds to position *c* in Fig. 8. The crankpin is held at this position by a long concentric portion of the cam 60, and while so held the stock is fed. After the stock has been fed to hook-receiving position the setting die 12 is depressed in consequence of a movement of the crankpin 64 from position *c* toward position *b*. This movement of the crankpin is caused by cam 62 for the purpose 65 of flaring the shank of the hook to a degree

commensurate with the thickness of the stock. Figs. 6 and 7 show the setting die before and after it is depressed in consequence of movement caused by cam 62, and it will be observed that the carrier 40 is provided with a hole 70 40' to receive the punch. For the purpose of depressing the setting die to the position shown by Fig. 7 the cam 62 acts upon a lever 67 which is mounted to rock upon a fulcrum 68. The lever has a roll 62' which is engaged by the cam. An adjustable screw 69 secured in the lever 67 transmits movement from the lever to a dog 70 which is formed upon or affixed to a sleeve 71. This sleeve is arranged upon the fulcrum 68 and 75 is provided with an arm 72. The dog 70 and arm 72 are rigid with relation to each other. The arm is arranged to engage the cam roll 61', and depresses the cam roll in consequence of operation of the cam 62. The cam 80 61, whose function is to raise the punch to its highest position after a setting operation, is formed with a notch or depression 73 (Fig. 10) to enable the roll 61' to be depressed by the arm 72. The dog 70 is held 85 against the screw 69 by a compression spring 74 arranged in a socket formed in the lever 67. By adjusting the screw 69 the relation of the arm 72 as to the lever 67 may be varied in such manner that the downward 90 movement which the setting die receives from the cam 62 may be varied. Referring once more to the movements of the crankpin 64, it will be observed that the punching movement is from *a* to *b*, the pressure-relieving movement is from *b* to *c*, the movement for determining the final setting of the hook is from *c* toward *b*, depending upon the adjustment of the screw 69, and the return movement from *b* back to *a*. The 95 feeding of the work occurs while the crankpin is at *c*. A notch 75 in the cam 61 receives the roll 61' at the moment when the punching stress is greatest, and is the counterpart of the nose 66 shown in Fig. 8. 100

I claim:

1. A machine for setting lacing hooks, comprising a stock support, a combined setting die and punch, means arranged to cause said punch to punch the stock on said support, means arranged to move said combined die and punch laterally while the punch is in the stock, to feed the stock to hook-receiving position, a hook carrier and its operating mechanism arranged to hold the 115 stock on said punch while the combined punch and die are moving to hook-setting position, and means for feeding lacing hooks, said hook carrier being arranged to carry a hook from said hook-feeding means 120 and force the hook through the stock and against said die to flare the hook.

2. A hook-setting machine, comprising a combined setting die and punch and a stock support arranged to coöperate with said 130

punch, means arranged to move said combined die and punch to punch the stock on said support, means arranged to move said combined die and punch laterally beyond said support while said punch is in the stock, to feed the stock to hook-receiving position, a hook carrier and operating means therefor arranged to support said carrier in stock-engaging position during the feeding 10 of the stock, to keep the stock on said punch, said operating means being arranged to move said carrier to insert the shank of a lacing hook in the stock on said punch and to flare said shank against said die, and

adjustable means arranged to move said 15 combined die and punch toward said carrier while said die and punch are in hook-flaring position, said adjustable means being adjustable to determine the final flaring of the shank according to the thickness of the 20 stock.

In testimony whereof I have affixed my signature, in presence of two witnesses.

ANDREW RAICHE.
